UNITED STATES PATENT OFFICE.

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY.

DESIGN FOR A GOLF-CLUB.

55,644.

Specification for Design.

Patented July 6, 1920.

Application filed March 27, 1920. Serial No. 369,447. Term of patent 7 years.

To all whom it may concern:

Be it known that I, WILLIAM F. REACH, a citizen of the United States, residing at Springfield, in the county of Hampden and State of Massachusetts, have invented a new, original, and ornamental Design for Golf-Clubs, of which the following is a

specification, reference being had to the accompanying drawing, forming part thereof.

The figure is a perspective view.

I claim:

The ornamental design for a golf club, as shown.

WILLIAM F. REACH.
